CHARLES F. MILLER, OF MOORES, PENNSYLVANIA, ASSIGNOR TO WESTINGHOUSE ELECTRIC & MANUFACTURING COMPANY, A CORPORATION OF PENNSYLVANIA

STOKER CONSTRUCTION

Application filed April 4, 1931. Serial No. 527,725.

My invention relates to combustion apparatus and more particularly to progressive feed stokers of the multiple retort underfeed type.

8 The invention has for an object to provide a structure of this type which is of improved construction and arrangement of parts.

A further object is to provide a structure of this character which is extremely strong 10 and durable, is very light and is cheap to manufacture.

A further object of my invention is to provide a composite beam structure consisting of an upper cast part and a lower steel tension rod. This structure permits the upper 15 cast or compression part to be made of minimum depth and thickness, whereby the ready ingress of air into the tuyère channels or spaces is interfered with to a minimum extent. Furthermore, as the tension rods are spaced from the cast compression portions of the composite beam structures, air may flow 20 freely underneath the cast portions of the beams and enter into the tuyère spaces or channels. Therefore, a further object of my 25 invention is to provide a composite beam structure of this character so that the distribution of air to the tuyère spaces or channels and the ready ingress of air into such 30 spaces or channels is facilitated.

These and other objects are effected by my invention as will be apparent from the following description and claims, taken in connection with the accompanying drawings, 35 and forming a part of this application, in which:

Fig. 1 is a longitudinal sectional view through a retort of a stoker constructed in accordance with the present invention;

40 Fig. 2 is a plan view of the stoker shown in Fig. 1, illustrating the arrangement of the retorts and tuyère rows, certain parts being omitted from portions of the stoker to illustrate more clearly the detail structure; and,

45 Fig. 3 is a fragmentary transverse section taken on the line III—III of Fig. 1.

According to the preferred embodiment of my invention which is shown on the accompanying drawings, I provide in a furnace, a 50 front and rear supporting structure and a

stoker of the type comprising parallel alternately-arranged retorts and rows of tuyères, which stoker extends between and is carried by the supporting structures. The stoker comprises a plurality of pairs of longitudinally-extending beams carried by the supporting structures, the beams of each pair being spaced apart a distance equal to the width of the retorts, a tension truss rod extending longitudinally beneath each beam and secured at its ends to the opposite end portions of its respective beam, a strut for spacing the rod from the beam, and tuyères and retort-forming elements carried by the beams and including upright plates secured 55 to the beams to form retort side walls.

Referring now in detail to the construction illustrated, the reference numeral 10 indicates a stoker of the downwardly inclined multiple retort type. The stoker comprises parallel, 60 alternately-arranged retorts 11 and rows of overlapping tuyères 12. The upper or front portion of the stoker is carried by a front supporting construction 13 including a transverse girder 14 and castings 15 bolted to the 65 upper face of the girder, and the lower or rear portion of the stoker is slidably carried by a rear supporting construction 16 comprising a girder 17 and castings 19 slidably supported by the girder 17.

The stoker is of fabricated construction and includes a supporting framework comprising a plurality of pairs of spaced supporting beams 18 carried at their upper and lower ends by the supporting constructions 13 and 16, respectively. The beams 18 of each pair are spaced apart a distance equal to the width of the retorts, and are held in this relation by the castings 15 and 19, the extremities of the beams being securely bolted to portions 70 of the castings. The pairs of beams are spaced apart a distance equal to the width of the tuyère rows, this being accomplished by constructing the castings in widths equal to the distance between the center lines of adjacent tuyère rows and in disposing the castings in abutting side-by-side relation upon their respective girders.

The beams 18 may be constructed of any suitable material, for example, cast iron. In 100

order that the beams be sufficiently strong to support the remaining parts of the stoker as well as the fuel bed and in order that the beams may be as light as possible, I provide 5 a tension truss rod 20 which is disposed beneath and longitudinally of each beam and is secured at its ends to brackets 21 and 22 formed on the opposite ends of each beam. A compression strut 23 depends from the central 10 portion of each beam and serves to space the truss rod from the beam. Adjustable tension means is provided for tensioning each rod 20. For example, the nuts 21a and 22a carried by the threaded ends of the rod may 15 be utilized for this purpose; however, each rod 20 is preferably divided intermediate its ends, and a turnbuckle 24 provided for tightening the rod and for facilitating its assembly and removal.

20 The beams 18 and 19 are separated from the heat of the fuel bed by more refractory cast metal parts of the stoker. These latter parts are the tuyères and the retort-forming elements. The retort-forming elements 25 comprise upright cast metal plates 25 bolted to the sides of the beams to form the retort side walls, and bottom forming members including guide or bottom plates 26 disposed between the side walls of each retort and supported by brackets 27 extending from the plates 25, and secondary rams 28 slidably supported by the plates 26. The overlapping tuyères 12 span the distance between and are supported by the adjacent side walls of adjacent retorts.

40 The operation of this type of stoker is well known. Green coal is fed into the ends of the retorts 11 from a hopper 30 by means of primary rams 37 reciprocating within ram boxes 32. The coal is advanced along the retort and forced upwardly and laterally onto the tuyère rows by the secondary rams 28. The resulting ash is discharged from the rear or lower end of the stoker by any suitable 45 means, not shown.

By reason of the fact that the stoker is constructed in the manner described, the beams which are an inherent part of the stoker structure may be relatively light, the major portion 50 of the required strength of the beams being supplied by the tension truss rods. The stoker may be extended to great lengths without necessitating the use of cumbersome and bulky stoker parts or the use of intermediate 55 supporting elements. The beams perform the load-carrying function of the retorts and are protected from the heat of the fuel bed by the tuyère and retort-forming elements. Furthermore, since each of the beams is reinforced by its tension rod, each beam may be 60 made of minimum depth and thickness, thereby minimizing interference on the part of the beams with free ingress of air into the tuyère channels or spaces. Also, as it is possible to minimize the depth of the beams due

to the presence of the tension rods and as the rods are spaced from their beams, the composite beam structures permit of the free flow of air between the rods and the beams proper and the ready entrance of air into the tuyère spaces or channels. The non-interference with the flow or distribution of air in an underfeed stoker is a matter of importance not only in supporting combustion more uniformly but in cooling the tuyères and preventing eddying which usually results in rapid burning out of tuyères subjected to eddying air or gas flow effects. Hence, the strains set up in the tuyère and retort forming elements due to heat are not transmitted 70 to the beams. Furthermore, if any of the tuyère or retort-forming elements should burn out, the affected part or parts may be readily replaced without disturbing the other structure.

Heretofore, cast iron supporting beams have been used to carry underfeed stoker retorts; however, such beams have usually been so constructed as to constitute the retort side walls. It has not been feasible to carry this construction to extreme lengths and furthermore it is objectionable on account of the beam element burning out. In accordance with the present invention, the beam elements do not constitute retort side walls but support 90 and position retort side walls formed separately therefrom, and each beam is of a composite character comprising an upper compression portion made of cast iron, which is very strong in compression, and a lower tension rod made of steel, whereby the beam may be made relatively light and is suitable for supporting very long retorts without the use of intermediate supports. This type of beam is particularly advantageous for supporting fuel contacting parts, as the cast iron compression portion thereof is inherently capable of withstanding high temperatures even though subjected to high compression stress, this being the portion of the beam 95 which is adjacent to the fuel bed. Also, as pointed out, due to the open girder formation of the beam, interference with distribution and supplying of air to the tuyère spaces or channels is interfered with to a minimum 100 extent.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In a furnace, the combination of spaced supporting structures, parallel, alternately-arranged retorts and rows of tuyères providing an inclined multiple retort underfeed 120

stoker extending between and carried by the supporting structures and comprising a plurality of pairs of longitudinally-extending parallel beam members carried by the supporting structures, the beams of each pair being spaced apart a distance equal to the width of a retort, a tension truss rod extending longitudinally beneath each beam and secured at its ends to the opposite end portions of its respective beam, a compression strut for spacing the intermediate portion of each rod from its beam, and tuyères and retort-forming elements carried by the beams and including upright plates secured to the beams to form retort side walls.

2. In a furnace, the combination of spaced supporting structures, parallel alternately-arranged retorts and rows of tuyères providing an inclined multiple retort underfeed stoker extending between and carried by the supporting structures and comprising a plurality of pairs of longitudinally-extending parallel beam members carried by the supporting structures, the beams of each pair being spaced apart a distance equal to the width of a retort, a tension truss rod extending longitudinally beneath each beam and secured at its ends to the opposite end portions of its respective beam, a compression strut for spacing the intermediate portion of each rod from its beam, adjustable means for tensioning each of said rods, and tuyères and retort-forming elements carried by the beams and including upright plates secured to the beams to form retort side walls.

In testimony whereof, I have hereunto subscribed my name this 2nd day of April, 1931.

CHARLES F. MILLER.
